UNITED STATES PATENT OFFICE.

ADALINE A. ROCKWELL, OF NEW YORK, N. Y.

DESIGN FOR RUCHES.

Specification forming part of Design No. 7,432, dated May 12, 1874; application filed April 28, 1874.
[Term of Patent 3½ years.]

To all whom it may concern:

Be it known that I, ADALINE A. ROCKWELL, of the city, county, and State of New York, have invented a Design for Ruches, of which the following is a specification:

The nature of my design is fully represented in the accompanying drawing, to which reference is made.

Figure 1 is a rear view of a ruche, in part, when open or extended in illustration of its form or figure. Fig. 2 is a cross-section of the same taken mainly as indicated by the line *x x*.

A represents the inner portion of the ruche, which is formed of a ruffle composed of loops *b*, which present a series of flutes having rounded edges *c*, said ruffles meeting below and spreading outward above. Outside of

this ruffle is a second ruffle, *B*, also composed of loops, presenting a series of flutes meeting below and spreading outward above, and having rounded edges *c'*, but said ruffle *B*, unlike the inner portion of the ruche, which is straight longitudinally, being of a waving form in direction of its length, establishing inner twists or twirls *d* on either side, and an outwardly and downwardly projecting bend or curved portion *e* at the center of its length in the rear.

What I claim as my invention is—

A design for ruches, substantially as described, and shown in the annexed drawing.

ADALINE A. ROCKWELL.
